UNITED STATES PATENT OFFICE

NAPOLEON GIARD, OF ROUGEMONT, QUEBEC, CANADA

TABLE

Application filed June 17, 1929. Serial No. 371,589.

The present invention relates to improvements in table construction and has particular reference to tables embodying extensible top sections.

Heretofore, tables of various characters have been known embodying extensible tops supported on a sliding mechanism to permit extension of the top. However, to properly manufacture a table of this construction and to ensure easy operation thereof, the slides had to be made very carefully and adjustment thereof was an operation of a delicate character which only a skilled workman could do.

Since the said slides were made of wood, it is easily conceived that climatic conditions affected the same to a great extent and that smooth operation of the table, together with utmost rigidity could not be guaranteed to a prospective customer, under all circumstances.

Therefore, it is the main object of the invention to provide a slide structure for extensible tables which is especially designed to afford convenient and durable operation and which is unaffected by climatic changes.

A further object of the invention is the provision of a top supporting slide for extensible tables constructed of metal so as to operate easily and without substantial noise.

Another object of the invention is the provision of a table having extensible top sections which are supported by an improved slide structure constructed of metal and adapted to be easily assembled by relatively unskilled labor and manufactured at negligible cost.

Other objects and advantages of the invention will become apparent as the description progresses.

In the accompanying drawings forming a part of this specification and in which like reference characters are employed to designate corresponding parts throughout the same:—

Figure 1 is a perspective view of a table in a contracted position,

Figure 2 is a similar view showing the top sections extended,

Figure 3 is a bottom plan view of the table with the top sections extended,

Figure 4 is a transverse sectional view taken on the line 4—4 of Figure 3,

Figure 5 is a perspective view of the slide construction and assembly, and

Figure 6 is an enlarged sectional view taken on the line 6—6 of Figure 3.

Referring to the drawings, wherein for the purpose of illustrations is shown a preferred embodiment of the invention, the numeral 10 generally designates the table in its entirety embodying vertical side and end panels 11 and 12 forming the table frame and having fixed on the upper edges of the side panels 11 relatively narrow side bars 13. At the centre of the table frame is mounted a relatively narrow transverse top strip 14 rigidly attached to the side panels 11.

Slidably mounted on the frame, at opposed sides of the centre strip 14, are horizontally slidable top sections, each of which includes a rigid portion 15 and a flexible portion 16 attached to the inner edge of the rigid portion. As shown to advantage in Figure 6, the slide sections are supported so that their upper surfaces will assume elevated positions with respect to the top surfaces of the side bars 13. This construction will obviate to a great extent the accumulation of matter in the slit between the side edges of the slide sections and the side bars and will enhance the appearance of the table top which, heretofore, has been of flush construction giving the slits at the sides an objectionable appearance.

An essential feature of the invention is the provision of a supporting slide structure for the slide sections. This slide structure embodies a slide mechanism designed to be mounted at the sides of the table frame to support each side of the extensible top sections. Each slide mechanism embodies a pair of complementary exterior bars 17 and 18 formed channel shaped in cross section.

The bars 17 are connected in longitudinal, horizontally extending positions to the inner sides of the frame side panels 11 and each is provided with a longitudinal slot 19, formed with an enlargement 20 at the inner

end. The slot 19 is arranged in registration with a groove 21 formed in the side panel 11, as shown to advantage in Figure 6. At the inner extremity of each bar 17, a roller 22 is mounted for vertical rotary movement by means of a screw 22', to form a guide for the flexible portion 16 of each top section. The complementary channel shaped bar 18, of each slide assembly, is attached to the outer face of a rail 23 secured to the lower surface of the rigid top portions 15 adjacent their side edges and is likewise provided with a longitudinally extending slot 24 disposed in registration with a groove 25 formed in the supporting rail. As clearly illustrated in Figures 5 and 6, the flanges of the channel bars 17 and 18, of each assembly, are directed toward one another to slidably engage opposed sides of an intermediate slide bar 26. The slide bar 26 is preferably rectangular in cross section and adapted to readily slide within the complementary support bars 17 and 18. Adjacent the inner end, the bar 26 carries a laterally and outwardly extending screw 27. The head of the screw is initially inserted through the enlarged opening 20 formed at the inner end of the slot 19, while the shank subsequently moves in the remaining major portion of the slot, the head thereof operating in the groove 21 of the table panel. Adjacent the opposed or outer end, each bar 26 carries an inwardly projecting transverse pin 28 adapted to extend through the slot 24 and into the groove 25. Thus, when the adjustable table top sections are in retracted arrangement, the side bars 17 and 18 and the intermediate slide bar 26 are disposed in substantially parallel positions, the flanges of the side bars projecting over the top and bottom edges of the intermediate bar, as shown in Figure 6. When the top sections are adjusted to extended positions, the intermediate bar 26 slides in the side channel bar 17 to its extreme outward limit and subsequently the inner side bar 18 slides upon the intermediate member 26 until the extreme outward movement of the top section is effected, the assembled bars assuming the position shown in Figure 5. It is contemplated to construct the channel shaped side bars 17 and 18 of metal, such as sheet metal, while the intermediate slide bar 26 is preferably formed of wood to provide an easily operable and durable slide construction. The inward sliding movement of the slide bar 26 is limited by means of a fixed pin 29 secured in a recess adjacent the inner end of the bar 17 and projecting inwardly to prevent the bar 26 contacting with the roller 22 and the bolt 27 from lateral movement through the enlarged aperture 20.

From this explanation, and as before stated, it will be realized that his new construction affords rapid and successful assembly of the slide mechanism by relatively un-

skilled labor and in a series of succeeding operations not necessarily done at the same time or by the same assembler. This is particularly important when it is considered that a plurality of assembling factories can be supplied with the parts of a table from a main manufacturing plant, and that said tables are adapted to be quickly put together in even a small shop without expensive planing machines, skilled labor or loss of time due to accurate adjusting of the table slide mechanism.

It is to be understood that the form of my invention herein shown and described is to be taken as a preferred example of the same, and that various changes as to the shape, size, and arrangement of parts may be resorted to without departing from the spirit of the invention or the scope of the subjoined claim.

Having thus described my invention, I claim:

A slide unit for extension tables, comprising a channel shaped guide having a web and a pair of right angular parallel facing flanges, the web of said guide having a longitudinal slot enlarged at one end, a complementary channel guide similar to the first and having flanges directed against the flanges of said first guide, said complementary guide having a longitudinal slot in the web thereof, a central slide bar fitting in the rectangular space defined inside the associated guides, screws secured at both ends of the slide bar, and on opposed faces thereof, the shanks of which screws extend through the slots provided in the guide webs, and means to secure said slide to an extension table whereby one guide will be attached to a stationary part of the table and other to a movable member of said extension table.

In witness whereof I have hereunto set my hand.

NAPOLÉON GIARD.
